DESIGN FOR A CLOCKCASE

Rudolph Vincent Basso, Medical Lake, Wash.

Application September 4, 1946, Serial No. 133,050

Term of patent 14 years

(Cl. D42—7)

To all whom it may concern:

Be it known that I, Rudolph V. Basso, a citizen of the United States of America, residing at Eastern State Hospital, Medical Lake, county of Spokane, State of Washington, have invented a new, original, and ornamental Design for a Clockcase, of which the following is a specification, reference being had to the accompanying drawing, forming a part thereof.

In the drawing:

Fig. 1 is a perspective of a clockcase embodying my design looking at the top and front thereof; Fig. 2 is a left hand elevation of such case; Fig. 3 is a right hand elevation of such case, and Fig. 4 is a rear elevation thereof.

I claim:

The ornamental design for a clockcase, as shown.

RUDOLPH VINCENT BASSO.
